ABSTRACT OF THE DISCLOSURE

The present invention provides a roof support wherein two distinct and different floor beams are rigidly, rather than flexibly, connected together in laterally-spaced substantially-parallel relationship by connecting means of a particular construction, the whole being designed to afford a passageway of maximum area parallel to the working face of the mine for passage of air, and a construction such as will protect a miner who must move through the passageway from falling material. To such ends one floor beam of a pair is of a length to carry, for example, two extendable props which cooperate to support a roof-engageable member, whereas the other such floor beam is longer, and carries, for example, three extendable props which themselves support an articulated roof-engageable member, of which one part is supported upon two of the three props—these two cooperating with the two props of the first-mentioned floor beam to define an orthodox "square"—and the other articulated roof-engageable member is supported upon the third of the three props. Each prop mounting, but not the prop per se, is located substantially within its floor beam, whereby the passageway is obstructed to a minimum degree, and includes resilient means urging the prop to a predetermined angular position relative to the floor beam (somewhat as is suggested in Patent No. 3,250,507), while allowing the prop a limited amount of angular movement relative to the floor beam.

This invention relates to roof supports suitable for use in mines.

Three sides of each floor beam, for example the top and two sides, may be formed from a single piece of material. The bases of the floor beams and a part of the connecting means may be formed from a single piece of material.

The connecting means between the floor beams may include two substantially-horizontal vertically-spaced connecting plates and two substantially-vertical horizontal connecting plates, the connecting plates and adjacent sides of the floor beams being integrally joined to form a torsion box.

The props carried by the two floor beams may carry the same roof-engageable member. Alternatively, and preferably, the props carried by one floor beam may carry a first roof-engageable member, and the props carried by the other floor beam carry a second roof-engageable member.

Reference to the drawings

One embodiment of the present invention will now be described, by way of example, with reference to the accompanying drawings, of which

FIGURE 1 is a plan view of a mine roof support,
FIGURE 2 is a side view of the roof support,

FIGURE 3 is a plan view of the lower part of the roof support, and

FIGURE 4 is a sectional view along the line 4—4 of FIGURE 3, with the props and part of their mountings removed.

2**Detailed description**

With reference to the accompanying drawings, a roof support suitable for use in a coal-mine includes a floor beam 3 carrying two fluid-pressure-operated telescopic props 4, and the lower end portion of each prop 4 is mounted in a prop mounting 5 located within the floor beam 3. The prop mounting 5 includes resilient means of known type urging the prop 4 to a predetermined angular position relative to the floor beam 3 while allowing the prop 4 a limited amount of angular movement relative to the floor beam 3. The prop mounting 5 shown in the drawing includes a series of precompressed rubber bodies 6 forming the resilient means, somewhat as shown in U.S. Patent 3,250,507. The two props 4 carry and are pivotally attached to a roof beam 7.

The roof support also includes a second floor beam 8 carrying three fluid-pressure-operated telescopic props 9, and the lower end portion of each prop 9 is mounted in a prop mounting, similar to the prop mounting 5, located within the floor beam 8. The props 9 carry and are pivotally attached to an articulated roof-engageable member formed by a forward and a rear roof beam 11, 12 respectively, connected together by a pivotal connection 13. The roof beam 11 is carried by the front prop 9, and the roof beam 12 is carried by the middle and rear props 9.

The floor beams 3, 8 are rigidly connected together in laterally-spaced parallel relationship by connecting means which in effect are integral with the two floor beams. In this embodiment the bases of the floor beams 3, 8 and a part of the connecting means are formed by a single plate-like base member 14. The top and two sides of the floor beam 3 are formed from a single piece of material 15 which is appropriately U-shaped and welded along its edges to the base member 14. Similarly, the top and two sides of the floor beam 8 are formed from a single piece of material 16 which is appropriately U-shaped and similarly welded to the base member 14.

The portion of plate or base member 14 which extends between the two floor beams 3, 8 forms a lower horizontal connecting plate 17 integral with and rigidly spacing apart the bases of the beams. The connecting plate 17 forms one part of the connecting means, which connecting means also includes an upper horizontal connecting plate 18, a forward vertical connecting plate 19 and a rear vertical connecting plate 21.

The upper connecting plate 18 is welded to the tops of the floor beams 3, 8. The forward vertical plate 19 extends between and is welded to the horizontal plates 17, 18 and is also welded to the adjacent sides of the floor beams 3, 8 at a position adjacent the rearward side of the front prop 4 of the support unit 1 and the rearward side of the middle prop 9 of the support unit 2. The rear vertical plate 21 extends between and is welded to the horizontal plates 17, 18 and is also welded to the adjacent sides of the floor beams 3, 8 at a position adjacent the rear ends of the floor beams 3, 8.

A shield 22 has its lower portion bolted to two lugs 23 welded to the rear ends of floor beams 3, 8, respectively, and its upper portion bolted to the upper ends of two struts 24 whose lower ends are bolted to two lugs 25 welded to the tops of the floor beams 3, 8, respectively. The shield 22 reduces the likelihood of coal or other mined material falling between the props 4 and the props 9 from a position rearwardly of the roof support.

At a position in front of the forward vertical plate 19, lugs 26 are provided for the attachment of a fluid-pressure-operated jack (not shown) to the roof support. In use of the roof support, the jack will be attached to an anchorage, for example a conveyor, so that the roof support can be advanced towards the anchorage by contracting the jack. The jack may be secured to the roof support

in conventional manner, such for instance as is shown in U.S. Ser. No. 443,421, filed Mar. 29, 1965.

In use of the roof support in a mine, the two horizontal connecting plates 17, 18, the two vertical connecting plates 19, 21 and the adjacent sides of the floor beams 3, 8 form a torsion box which resists relative movement of the floor beams 3, 8, as these floor beams are acted upon by diverse forces.

The floor beams 3, 8 and the connecting means form a rigid base in which the prop mountings 5 are located, and this rigid base has a relatively small height compared to the overall height of the roof support. Thus the roof support has a relatively large passage for gas flow in a direction transverse to the length of the floor beams 3, 8. Also, the described roof support possesses the necessary strength to function satisfactorily in a mine without being unduly heavy.

I claim as my invention:

1. An advanceable roof support including two floor beams, one of which is longer than and has a forward portion thereof extending beyond the advancing end of the other, means rigidly connecting said floor beams in laterally spaced substantially parallel relationship, two extendable props carried generally upright on each floor beam, the four props being located to define generally a square, a third prop carried on the aforesaid forward portion of the longer floor beam, in advance of the other two props thereon, a roof-engageable member carried on the two first-mentioned props on each floor beam, an additional roof-engageable member carried on the aforesaid third prop on the longer floor beam, and hingedly

connected to the first mentioned roof engageable member on said longer floor beam, and a plurality of mountings, one for each prop on each floor beam, and resilient means interposed between each prop and its mounting, acting to urge the prop into a predetermined angular position relative to its floor beam.

2. The advanceable roof support according to claim 1 wherein the top and sides of each floor beam are formed by a single channel-shaped piece of material, and the two pieces of material are rigidly interconnected by a plate extending thereunder.

3. The advanceable roof support according to claim 1 wherein the mutually adjacent sides of the floor beams are rigidly interconnected by pairs of horizontally and vertically disposed plates forming a torsion box therewith.
